UNITED STATES PATENT OFFICE.

JOHN M. WALTON, OF NEW ORLEANS, LOUISIANA.

INTERNAL-COMBUSTION ENGINE.

1,232,632.

Specification of Letters Patent. Patented July 10, 1917.

Application filed January 19, 1912. Serial No. 672,195.

To all whom it may concern:

Be it known that I, JOHN M. WALTON, a citizen of the United States, and a resident of New Orleans, in the State of Louisiana, have invented a certain new and useful Improvement in Internal-Combustion Engines, of which the following is a specification.

My invention relates to internal combustion engines and among its objects are the elimination of unnecessary parts and the simplification of the structure of the motor, the provision of a motor of increased efficiency without increase of bore or stroke, doing away with all recesses or gas pockets 10 in communication with the interior of the cylinder, the use of a single cylinder port both for intake and exhaust; the provision of a single rotary valve for controlling both the intake and exhaust; the provision of a 15 novel form of rotary valve comprising an expanding member which will always be in close contact with the walls of its chamber, thus preventing all leakage of gases; and with the foregoing and related objects in 20 view, my invention consists in the parts, improvements and combination hereinafter set forth and claimed. While I show and describe a specific form or forms in which 25 my invention may be embodied, it is nevertheless to be understood that my invention is not confined to such specific form or forms but that its scope is as set forth in the claims.

In the accompanying drawings, forming a part of this specification, and wherein the 30 same reference numerals are applied to the same parts throughout, Figure 1 is a view partly in side elevation and partly in longitudinal, central cross-section of a 4 cylinder internal combustion engine embodying 35 my invention. Fig. 2 is an elevational view of my improved rotary valve. Fig. 3 is a cross-sectional view of said valve on the line 3—3, Fig. 2. Fig. 4 is a cross-sectional view of said valve on the line 4—4, Fig. 2. Fig. 5 is a cross-sectional view on the line 45 5—5, Fig. 1. Fig. 6 is a detail elevational view showing one form of gearing for driving the rotary valve shaft from the engine shaft, and Figs. 7, 8, 9 and 10 are diagrammatic views showing the four cycles of the 50 engine and the positions of the rotary valve corresponding thereto.

My invention is applicable to engines having but a single cylinder or to engines 55 with any desired number of cylinders. Each

cylinder of an engine embodying my invention is provided with but a single port which, for the purpose of convenient reference, will be termed the cylinder port. This port preferably has the form of a long 60 slot, the length of the slot being substantially equal to the diameter of the cylinder bore. In the construction shown the cylinder port extends substantially across the head of the cylinder in a line parallel to the 65 longitudinal axis of the crank shaft. Ample cross-sectional area of the port may therefore be secured even when the port is made comparatively narrow, as its area may readily be increased by a slight increase in 70 its width.

The valve which governs the inflow and discharge of gases through this single port, is of the type commonly known as a rotary valve, and such valve is provided with suitable passages in its periphery to properly control the inflow of gases to the engine cylinder from the intake manifold, which is situated on one side of the rotary valve and the discharge of exhaust gases to the exhaust 80 manifold which in the preferable form is situated upon the opposite side of the rotary valve from the intake manifold. This construction may be readily taken advantage of in the designing of the engine as the entire valve structure and the intake and exhaust manifolds may be comprised within an upward continuation of the cylinder walls, thus giving a smooth and simple exterior and very pleasing lines as well as 85 an extremely simple form of construction. Provision is preferably made for cooling the rotary valve and the manifolds by providing water passages substantially surrounding the valve chamber through which the water 90 may pass in quantities which will secure an ample cooling effect for these parts.

Referring to the drawings, I have designated the crank case of the engine selected for the purpose of illustration by the reference numeral 1. This crank case has the vertical cylinders 2 formed in any well known manner secured thereto and extending in vertical direction therefrom in line with one another longitudinally of the engine. The cylinders may be cast separately or any desired number may be cast together or the cylinders may be cast integrally with a portion of the crank case, or they may be formed in any other desired manner. The 100 105 110

pistons 3, 3, the connecting rods 4, 4 and the crank shaft 5 are of any ordinary and well known construction.

The casting 6 containing the rotary valve 5 and forming the cylinder head or heads is preferably made separately from the cylinders themselves, and is so constructed as to be readily capable of attachment to the cylinders, its form depending upon the 10 method of formation and assembly of the cylinders themselves.

Such casting is preferably integral and is secured on top of the open cylinders and extends the entire length of the engine and 15 it preferably contains on one side the exhaust manifold 7 and on the opposite side the intake manifold 8. The casting 6 is preferably hollowed out as shown at 9, Fig. 5 to form a dome shaped head for each cylinder and the cylinder ports 10 in the form 20 of engine illustrated extend across the entire width of the cylinder head centrally thereof and in line with the longitudinal axis of the engine. A cylindrical valve 25 chamber 11 is formed centrally of the casting 6 and extends substantially from end to end thereof, and within this cylindrical valve chamber is received the rotary valve 12 comprising the sleeve 13 and the substantially cylindrical core 14. The valve 30 chamber communicates with the exhaust manifold 7 through the exhaust port 15 and with the intake manifold 8 through the intake port 16. The passages within the valve 35 for the flow of gases to and from the several cylinders are indicated by the reference numeral 18.

The detail construction of the valve 12 is shown in Figs. 2, 3 and 4 of the drawing. 40 The core 14 fits within the ring or sleeve 13 and is secured thereto as for example by means of the key 19 so that core and ring or sleeve rotate together and without independent rotary movement. The passages 45 18 extend peripherally part way around the valve 12, the sleeve 13 being entirely cut away in the formation of such passages and the passages also being preferably extended within the material of the core 12 somewhat 50 by the peripheral cutting away of a portion of such core to complete the formation of the passages. These passages 18, in the valve 12 are arranged in such manner as to control the induction and ejection of 55 gases to and from the various cylinders in any of the ordinary well known methods of rotation, the cycles recurring, for instance, in the ordinary four-cylinder type of engine, in the usual 1-3-4-2 order.

60 Provision is made for expansion and contraction of the valve due to the extremes of temperature to which it is necessarily subjected in the operation of the motor, not only by its formation in two parts, an inner 65 core and an outer sleeve, but also by cut-

ting narrow slots 20 through the material of the sleeve 13 preferably in the narrow sections thereof between adjoining passages 18. This provides for expansion and contraction of the sleeve in precisely the same 70 manner as in the case of the expansion rings with which the engine cylinders are equipped. It is to be understood that before the completed valve 12 is introduced within the valve seat, the tendency of the sleeve 75 13 is to expand outwardly and that in order to introduce the valve within the valve chamber it is necessary to compress the sleeve 13 upon the core 14 and that when it has been introduced therein the tendency 80 toward expansion so created results in the valve fitting tightly within its cylindrical seat. The expansion of the valve produced by becoming heated in operation is taken care of by this construction so that although 85 the valve is at all times tightly and firmly received within its seat, the heating of the valve will not result in its binding or "freezing" within the valve chamber as sometimes occurs with valves of the ordinary rotary 90 type when subjected to a considerable degree of heat. As the gases do not come into contact with the valve except at a small portion of its periphery the valve is protected from becoming overheated and the 95 cooling of the valve in operation is partly due to the fact that after being swept by the heated gases of the exhaust the same passages are immediately subjected to the cooling effect of the inflowing charge. A 100 valve so constructed has ample cross-sectional area in all its parts to resist any tendency to be deformed or buckled by the heat. The arrangement of the passage 18 within the periphery of the valve 12 results in the valve being very cool in its 105 operation as compared with the former rotary valves in which it was proposed to conduct the heated gases away through openings 110 extending centrally of the valve, which resulted in the valve being greatly heated and frequently distorted. The edges of the sleeve 13 at the ends of passages 18 are under-cut, so as to leave substantially sharp 115 knife edges 18^a at these points, which greatly assist in keeping the interior of the valve chamber free of carbon and preventing the clogging and fouling of the valve and valve chamber. Whereas the ports 10, 15 and 16 extend longitudinally of the valve 120 chamber 11, their edges substantially forming elements of the hollow cylindrical surface thereof, the edges of the passages 18 preferably extend at a slight angle to such 125 longitudinal direction, as shown at 18^b so as to prevent any catching or binding effect which might possibly result if the edges of the ports and passages were parallel to one another.

Any suitable form of bearing may be pro- 130

vided for the improved valve. I prefer, however, to mount the valve in ball bearings 21 at each end thereof, and which are removed a sufficient distance from the engine 5 cylinders so as not to become unduly heated. The valve structure for the entire engine being rigidly connected together, all that is needed for its operation is the provision of 10 means for rotating the valve at proper speed applied at any point within its length. This fact is also conducive to simplicity of design and to the securing of a smooth exterior and it is possible to transmit motion with the required reduction of speed direct 15 from the crank shaft to the rotary valve shaft in a variety of ways. In order to secure quietness of operation and extreme closeness of working the method of transmitting rotation from the crank shaft to the 20 valve shaft, which I have illustrated, comprises spiral gears 22 and 23 upon the crank shaft and valve shaft respectively and co-operating spiral gears 24 and 25 upon the vertical shaft 26 mounted in properly arranged 25 bearings and extending vertically of the engine as shown in Fig. 6.

Additional spiral or other gears such as 27, may be placed on the vertical shaft 26 at any point within its length to operate 30 devices connected directly or indirectly with the engine such as a pump, magneto or the like as shown on Fig. 1. Such driven shaft may extend horizontally across the engine 35 thus permitting the mounting of the pump and magneto or timer in positions where the same will be conveniently accessible. If desired an oil pump may be operated from the spiral gear 22 through the gear 28. I 40 prefer to arrange the vertical shaft 26 at the end of the engine opposite the fly wheel and to provide a cover plate 29 therefor, this making these parts dust proof, giving the engine a smooth exterior and silencing 45 the gears and shaft for driving the rotary valve and at the same time being readily removable to permit access when necessary. Means for preventing longitudinal movement 50 of the valve 12 are provided, such means may take the form of a thrust bearing 30 as shown in Fig. 1.

The spark plugs or other ignition devices for my improved engine are preferably inserted in orifices provided for that purpose 55 immediately beneath the intake manifold and extending at an angle of about 45° to the vertical as is clearly shown in Fig. 5. Suitable openings 31 are provided at the upper portion of the valve chamber 11 for 60 the purpose of supplying lubricating oil to the valve 12. Oil is preferably fed to this valve by means of a force feed, so that an ample supply of oil at all times is assured, the supply being delivered at the highest 65 point of the valve, which distributes the oil

entirely around the valve chamber as it is rotated. The cored out water spaces 32 which are provided within the casting 6 and which substantially surround the valve structure on all sides are of sufficient dimension 70 to carry an ample supply of water to prevent the over heating of the valve at all times. The provision for water supply is preferably increased somewhat on the exhaust side of the engine as this side is likely 75 to be considerably hotter than the intake side.

In order to prevent the hottest portion of the engine exhaust from reaching the valve 12, I prefer to provide an auxiliary exhaust 80 port 33, which is opened by the over-running of the piston. Inclined vanes or flanges 34 are provided in order to secure a suction effect in connection with the auxiliary exhaust and to dispense with the necessity of 85 check valves or other means for preventing back pressure.

The operation of my improved engine will be apparent from the foregoing, particularly when considered in connection with 90 the diagrammatic views of Figs. 7-10. As shown in these figures the direction of rotation of the valve 12 is anti-clockwise or in the opposite direction to the motion of the crank shaft which rotates in a clockwise direction, the relative speeds of rotation being of course as 1 to 2. This relative direction of rotation of course depends upon which side of the engine is selected to contain the exhaust and intake manifolds respectively. 100 In Fig. 7 the piston is shown at the top of its stroke, at the moment when the exhaust through the manifold 7 has ceased and the intake through the manifold 8 is to begin. As the piston travels downward the valve 12 105 rotates in the direction of the arrow at the top of Fig. 7 and the intake of the gas from the manifold 8 is continued until the piston reaches the bottom of the stroke or just past the bottom of the stroke, at which point the 110 communication from the intake manifold 8 to the interior of the cylinder is closed, the passage 18 having passed port 10. The piston now passes upward and compresses the 115 gas, the position of greatest compression being shown at Fig. 9. Ignition takes place at or about this point and the piston is driven downward. As it approaches the lowest position the auxiliary port 33 is uncovered, permitting the discharge of the 120 hottest portion of the cylinder's contents. The exhaust port 15 is opened at this point and remains open during the upward travel of the piston as indicated in Fig. 10. As the rotary valve is arranged to open and 125 close the ports by travel across them in the direction of their width and as the slots being very long may be made relatively very narrow, the opening and closing of the valves is accomplished in a minimum of 130

time, and as the valve is opened and closed about the times that the pistons are at their extreme top or bottom positions and the vertical component of their movement is 5 relatively very small it results that the valves are entirely opened or entirely closed within times corresponding to an excessively small vertical movement of the pistons. It will of course be understood that the degree 10 to which the passage 18 is extended around the valve 12 and the precise relative angular positions of the ports 10, 15 and 16, may be varied within certain limits in order to produce the most effective results, depending 15 principally upon the speed at which the engine is to be operated.

It will be apparent that in addition to the numerous advantageous features already set out, engines constructed in accordance with 20 my invention are extremely quiet in operation and the moving parts thereof being very few in number and provided with ample bearing surfaces scarcely any wear is evident over long intervals so that the quietness of operation remains even after a long 25 period of use.

Having now described my invention I claim:

1. A rotary valve for internal combustion 30 motors of generally cylindrical form and

comprising a core solid at its center, and an expansion sleeve about said core, said valve being provided with peripheral gas passages, the edges of said passages forming an angle with the elements of the cylindrical 35 valve, substantially as set forth.

2. A rotary valve for internal combustion motors comprising a massive central core and an expansion sleeve surrounding said core and connected thereto so as to rotate 40 therewith, said valve being provided with gas passages extending entirely through said sleeve and for a distance about the periphery of the valve but not extending to any substantial distance within the material 45 of the core, substantially as set forth.

3. In an internal combustion motor, a cylinder, a cylindrical valve casing communicating with said cylinder by a single port and provided with inlet and exhaust ports, 50 a solid massive rotary valve in said casing, said valve being provided with a peripheral gas passage, an edge of said passage making a sharply acute angle with the elemental lines of the cylindrical valve, substantially 55 as set forth.

JOHN M. WALTON.
